UNITED STATES PATENT OFFICE.

CHARLES R. UEBELMESSER, OF NEW YORK, N. Y., ASSIGNOR, BY MESNE ASSIGNMENTS,
TO AMERICAN STANDARD MOTION PICTURE MACHINE COMPANY, INC., OF NEW
YORK, N. Y., A CORPORATION OF NEW YORK.

WINDING APPARATUS.

1,145,633.

Specification of Letters Patent.

Patented July 6, 1915.

Application filed April 25, 1908, Serial No. 429,135. Renewed November 25, 1914. Serial No. 874,093.

To all whom it may concern:

Be it known that I, CHARLES R. UEBELMESSER, a subject of the Emperor of Germany, and a resident of the city, county, and State of New York, United States of America, have invented certain new and useful Improvements in Winding Apparatus, of which the following is a specification.

My invention relates to new and useful improvements in winding apparatus and consists in the novel construction and arrangement of parts herein shown and described, the novel features of which are set forth in claims.

Referring to the drawings, Figure 1 is a side elevation, partly in section, of a portion of a moving picture machine with my invention applied thereto. Fig. 2 is a rear end elevation of the parts shown in Fig. 1, with some of them broken away to more clearly show the construction. Fig. 3 is a sectional plan view of the apparatus shown in Fig. 1, the section being taken on the line 3—3 of the latter figure. Fig. 4 is a plan view of the parts shown in Fig. 1. Fig. 5 is a sectional rear elevation on an enlarged scale of the winding mechanism which I have invented showing some details of its construction. Fig. 6 is a perspective view of certain parts of my invention illustrating the operation of the apparatus.

Like characters of reference designate corresponding parts in all of the figures.

10 designates the casing or frame of a moving picture machine of ordinary construction. 11, 11 are brackets projecting from the upper portion of this casing and arranged to support a shaft 12 upon which a reel 20 may be mounted. 13 is a sprocket-wheel affixed to the shaft 12. Projecting from the lower portion of the casing 10 is a supporting frame 14 which supports the vertical spindle 30 and other parts which will be pointed out later.

14^A is a bridge-piece extending over the top of the supporting frame 14. One end of this bridge-piece is hinged at 14^B and the other end is arranged to be connected with the supporting frame by a spring-catch 14^C.

15 are brackets affixed to the supporting frame which form bearings for a shaft 16, to the outer end of which is affixed a sprocket-wheel 17.

18 is a sprocket-chain connecting the sprocket-wheels 13 and 17. 55

19 designates a bevel-gear affixed to the inner end of the shaft 16.

21 is a rotary receiving member which is in the form of a short hollow cylinder with a closed base 22. The internal diameter of 60 the vertical flange or wall of this cylinder is preferably about equal to that of the outer diameter of the film upon reel 20. The central portion of this base is carried down through the supporting frame 14 in the 65 form of a hollow circular hub 23. The center of the frame 14 is constructed to form a bearing for this hub, and a washer 24 may be interposed between the base 22 and the upper surface of the frame 14 to allow the 70 receiving member to rotate freely within the frame.

25 is a bevel-gear affixed to the hub 23 and in mesh with the bevel-gear 19. The gear 25 is of slightly greater diameter than that of 75 the gear 19. The spindle 30 passes freely through the center of the hub 23 and extends into the center of the receiving member 21. At the upper end of this spindle 30 a driving spool 31 is affixed. This spool 80 comprises near its upper and lower edges two sets of projecting teeth 32.

33 is an auxiliary guiding spool, the upper and lower flanges of which bear upon the teeth 32 so that the rotation of spool 31 85 is transmitted to the spool 33. The vertical support 34, upon which spool 33 is rotatably mounted, is slidably supported in a slot 14^D in the bridge 14^A. A spring 35 is provided for pressing the support 34 toward the center of the frame and keeping the flanges of spool 33 in contact with teeth 32 of the driving spool 31. 90

36 is a bevel-gear affixed to the lower end of the spindle 30 and in mesh with a similar 95 bevel-gear 37 rigidly mounted upon a shaft 38 which is mounted in the brackets 15 and has affixed to it a sprocket-wheel 39. In Fig. 5 this shaft 38 is shown divided with its two parts connected together through a friction drive connection 38^A.

40 is a motor driven shaft upon the upper and lower ends of which are affixed driving gears 41 and 42 which are in mesh with and arranged to drive other gears 43 and 44. 105 The latter gears are arranged to rotate two

driving spools 45 and 46, similar in construction to the spool 31, and, like the latter, having auxiliary guiding spools associated with them. 47 is another driving spool arranged 5 to be rotated from the shaft 40 with an intermittent motion through intermediate mechanism which is not shown, as it is a common part of a moving picture machine and forms no part of the present invention.

10 48 is a sprocket-wheel connected to rotate with the gear 44 and the driving spool 46. A sprocket-chain 49 connects this sprocket-wheel 48 with the sprocket-wheel 39.

15 50 is a film such as is used in a moving picture machine and is provided along its edges with the usual series of perforations 51. The teeth upon all of the driving spools above pointed out are designed and spaced to fit into these perforations and to impart 20 to the film the desired movements.

25 The various parts of this apparatus have now been pointed out, and I will proceed to describe their operation. The film 50 is wound up and is carried by the reel 20. The latter is then placed upon the shaft 12, to 30 which it is keyed, and the end of the film carried down over the driving spools 45, 47, 46 and 31. Now, when the motor driven shaft 40 is rotated, all of these driving spools will be rotated at an equal rate of 35 speed, and the spool 47 will be given the additional intermittent movement before mentioned. This will cause the film to be unwound from the reel 20 at a certain rate of speed, and to be pushed at the same time and at the same rate of speed by the driving spool 31 into the receiving member 21. The internal diameter of the receiving member is made approximately equal to the external diameter of the film 50 when the latter is all wound upon the reel 20. It may be seen that the unwinding of the film from the 45 reel will cause the latter to be rotated. As the film is unwound at a uniform rate, the rate of rotation of the reel will increase as the outside diameter of the film remaining upon the reel decreases. The mechanical connections between the reel and the receiving member are such that this variable rotation of the reel will be transmitted to the receiving member so that the speed of the latter will increase as the internal diameter of the film, which is being coiled up within it, gets smaller. In order that this coiling up 55 of the film within the receiving member be made properly, it is important that the internal circumferential speed of the film within the receiving member be not faster than the lineal speed of the film past the driving spools. In fact it is preferable to 60 make this circumferential speed somewhat slower so that the film will pack itself together. When the connections are made to produce this result the non-positive friction 65 drive connection 38^a is interposed in the

shaft 38 to allow for slip and to prevent buckling of the film within the receiving member. As some of the films are shorter than others—and consequently their diameter, when wound up and placed upon reel 20, is smaller—one or more rings or collars 21^a of desired thicknesses may be provided which may be inserted within the receiving member as shown in section in Fig. 5 before the beginning of the operation 75 to compensate for this difference. After the film has been entirely unwound from the reel 20 it will have been coiled up within the receiving member with its end which was originally on the inside of the reel 20 now 80 on the inside of the coil within the receiving member. The bridge-piece 14^a of the supporting frame may now be removed, and the wound up coil replaced upon the reel 20 or placed upon another similar reel, one side 85 of which is made removable for this purpose. A reel so constructed is fully described in a pending application for patent filed by me March 31st, 1908, bearing Serial Number 424,312. 90

95 I have shown my invention as applied to a moving picture machine as this forms a convenient example and illustration of its operation and use. I by no means wish to limit myself to this particular use as the invention is applicable to many other forms of apparatus; in fact to nearly any case where a reel of material is to be coiled or wound up a plurality of times in the same direction or order. The perforated paper 100 rolls of mechanical players is an example of such use. In such devices the rollers when used are wound up on a reel or spindle and have to be unwound to get them again in proper position for being used. 105

What I claim is.—

110 1. In an apparatus for unwinding and winding a flexible strip, a hollow rotatable receiving member for the strip, means for positively delivering the strip to the inner periphery of the receiving member, and means for rotating the receiving member at a variable rate proportional to the rate of movement of the strip within said member.

115 2. In an apparatus for unwinding and winding a flexible strip, a hollow cylindrical receiving member for the strip, means for positively delivering the strip to the inner periphery of the receiving member so as to coil it upon itself at a fixed rate of speed, and means for rotating the receiving member at an increasing rate proportional to the rate of peripheral movement of the inner convolutions of the strip-coil within 120 said member.

125 3. In an apparatus for unwinding and winding a flexible strip, a hollow rotatable cylindrical receiving member for the strip, means for pushing the strip into the receiving member against the inner wall thereof 130

- and coiling it upon itself, a reel constructed to deliver the strip from the outer periphery of the strip roll and driving connections between the reel and the receiving member 5 whereby the receiving member is rotated at an increasing rate proportional to the speed of the strip and to the rate of peripheral movement of the inner convolutions of the strip-coil within said member.
- 10 4. In an apparatus for unwinding and winding a flexible strip, a reel upon which the strip may be placed in the form of a coil wound in one direction, means for unwinding said strip-coil from its outer periphery, 15 coöperating means in which the strip may be wound into a coil from the inside in the same direction as that in which it is wound on the reel and mechanism for rotating said coöperating means.
- 20 5. In an apparatus for unwinding and winding a flexible strip, a reel constructed to deliver the strip from the outer periphery of a roll, a hollow cylindrical receiving member, means for unwinding the strip 25 from the reel and for positively delivering said strip to the inner periphery of the receiving member, and driving connections between the reel and the receiving member whereby the receiving member is rotated at 30 a rate proportional to that of the rotation of the reel.
6. In an apparatus for unwinding and winding a flexible strip, a reel constructed to deliver the strip from the outer periphery 35 of a roll thereon, a hollow cylindrical receiving member, mechanism for unwinding the strip from the reel to thereby rotate the reel, said mechanism being arranged to push the strip into the receiving member against 40 the inner wall thereof, and means for transmitting the rotation of the reel to the receiving member.
7. In an apparatus for unwinding and winding a flexible strip, a reel constructed 45 to deliver the strip from the outer periphery of a roll thereon, a hollow cylindrical receiving member, a plurality of positively rotated driving spools arranged to unwind the strip from the reel and to thereby rotate the 50 reel, the rotation of said spools being arranged to push the strip into the receiving member against the inner wall thereof, and driving connections between the reel and the receiving member for transmitting the rotation of the reel to the receiving member.
8. In an apparatus for unwinding and winding a flexible strip, a shaft, a reel positively mounted upon said shaft and constructed to deliver the strip from the outer 60 periphery of a roll thereon, a hollow cylindrical receiving member, a plurality of positively rotated driving spools arranged to unwind the strip from the reel and to thereby rotate the reel, the rotation of said spools being arranged to push the strip into the receiving member

ceiving member against the inner wall thereof, actuating mechanism for rotating the receiving member, and connections between the reel shaft and said actuating mechanism for transmitting the rotation of the reel to 70 the receiving member.

9. In an apparatus for unwinding and winding a flexible strip, a reel positively mounted upon said shaft and constructed to deliver the strip from the outer periphery 75 of a roll thereon, a hollow cylindrical receiving member of substantially the same internal diameter as the outside diameter of the strip-roll upon the reel, a plurality of positively rotated driving spools arranged 80 to unwind the strip from the reel and to thereby rotate the reel, the rotation of said spools being arranged to push the strip into the receiving member against said flange, actuating mechanism for rotating the receiving member, and connections between the reel shaft and the actuating mechanism for transmitting the rotation of the reel to the receiving member.

10. In an apparatus for unwinding and winding a flexible strip, a shaft, a reel positively mounted upon said shaft and constructed to deliver the strip from the outer periphery of a roll thereon, a hollow cylindrical receiving member, a device arranged 90 to change the internal diameter of the receiving member to correspond with the external diameter of the flexible strip-coil upon the reel, a plurality of positively rotated driving spools arranged to unwind the strip 95 from the reel and to thereby rotate the reel, the rotation of said spools being arranged to push the strip into the receiving member against the inner wall thereof, actuating mechanism for rotating the receiving member, 100 and connections between the reel shaft and the actuating mechanism for transmitting the rotation of the reel to the receiving member.

11. In an apparatus for unwinding and winding a flexible strip, a hollow cylindrical receiving member, means for pushing said strip into the receiving member against the inner wall thereof, and driving means for 110 rotating the receiving member at an increasing rate, proportional to the rate of peripheral movement of said strip within the receiving member, but with its internal peripheral speed less than the speed of the strip.

12. In an apparatus for unwinding and winding a flexible strip, a reel upon which the strip may be wound, a hollow cylindrical receiving member, means for unwinding the strip-coil from the reel and pushing it 115 into the receiving member at a fixed rate of speed, said means being arranged to rotate the reel, and driving means actuated by the rotation of the reel for rotating the receiving member slower than the rotation of the 120 strip.

reel and at a rate proportional to the rate of rotation of the reel.

13. In an apparatus for unwinding and winding a flexible strip, a reel upon which the strip may be wound, a hollow cylindrical receiving member, mechanism for unwinding the strip from the reel, said mechanism being arranged to rotate the reel and to push the strip into the receiving member 10 at a fixed rate of speed, and driving means actuated by the rotation of the reel for rotating the receiving member at a rate slower than that of the rotation of the reel.

14. In an apparatus for unwinding and 15 winding a flexible strip, a shaft, a reel positively mounted upon said shaft and constructed to deliver the strip from the outer periphery of a roll thereon, a hollow cylindrical receiving member, a plurality of positively rotated driving spools arranged to 20 unwind the strip from the reel and to thereby rotate the reel, and to push the strip into the receiving member, actuating mechanism for rotating the receiving member, driving connections between the reel shaft and the actuating mechanism for transmitting the rotation of the reel to the receiving member at a slower rate of rotation, and a yieldable joint between said actuating 25 mechanism and the driving spools.

15. In an apparatus for unwinding and winding a flexible strip, a shaft, a reel positively mounted upon said shaft and constructed to deliver the strip from the outer 30 periphery of a roll thereon, a hollow cylindrical receiving member having a flange of substantially the same internal diameter as the external diameter of the strip-coil upon the reel, a plurality of positively rotated 35 driving spools arranged to unwind the strip from the reel and to thereby rotate the reel and its shaft, and to push the strip into the receiving member, actuating mechanism for rotating the receiving member, connections 40 between the reel shaft and the actuating mechanism for transmitting the rotation of the reel to the receiving member at a slower rate, and a 45 yieldable friction joint between said actuating mechanism and the driving 50 spools.

16. In an apparatus for unwinding and winding a flexible strip, a shaft, a reel positively mounted upon said shaft and constructed to deliver the strip from the outer 55 periphery of a roll thereon, a hollow cylindrical receiving member, a device for changing the internal diameter of the receiving member to substantially correspond with the external diameter of the strip-coil upon the 60 reel, a plurality of positively rotated driving spools arranged to unwind the strip from the reel and to thereby rotate the reel and its shaft, and to push the strip into the receiving member at a fixed rate of speed, an actuating 65 shaft, and gearing arranged to rotate

the receiving member, driving connections between the reel shaft and the actuating shaft for rotating the actuating shaft at a slower rate than that of the reel shaft, and a 70 yieldable friction joint between said actuating mechanism and the driving spools.

17. In an apparatus for unwinding and winding a flexible strip, a horizontal shaft, a reel positively mounted upon said shaft and constructed to deliver the strip from the 75 outer periphery of a roll thereon, a horizontally disposed hollow cylindrical receiving member having a vertical flange, means for changing the effective internal diameter of the receiving member flange to substantially 80 correspond with the external diameter of the strip coil upon the reel, a supporting frame and a pivoted bridge-piece rotatably supporting the receiving member, a plurality of positively rotated driving spools arranged to 85 unwind the strip from the reel and to thereby rotate the reel and its shaft, and to push the strip at a fixed rate of speed against the inner periphery of the flange of the receiving member to coil said strip up 90 upon itself from the inside, a shaft and gearing actuated by the rotation of the reel and arranged to rotate the receiving member at a slower rate than that of the rotation of the reel, a sprocket-chain connecting 95 the reel shaft and the actuating shaft, a 100 yieldable friction joint between said actuating mechanism and the driving spools.

18. In combination with a moving picture machine, a horizontal shaft, a reel positively 105 mounted upon said shaft and constructed to deliver a film from the outer periphery of a roll thereon, a horizontally disposed hollow cylindrical receiving member with an internal diameter substantially 110 corresponding with the diameter of the film-coil upon the reel, a supporting frame and a hinge-piece rotatably supporting the receiving member, means for raising said bridge-piece, a plurality of positively rotated driving 115 spools arranged to engage with and to unwind the strip from the reel and to thereby rotate the reel and its shaft, and to push the film at a fixed rate of speed against the inner periphery of the flange of the receiving member to coil said film up upon itself 120 from the inside, a shaft and gearing actuated by the rotation of the coil and arranged to rotate the receiving member at a slower rate than that of the rotation of the reel, a 125 sprocket-chain connecting the reel shaft and the actuating shaft, and a yieldable friction joint between said actuating mechanism and the driving spools.

19. In motion picture apparatus, a film 125 reel constructed to deliver the film from the outer periphery of the film roll, a hollow rotatable receiving member for the film, means for positively delivering the film to the inner periphery of the receiving member, 130

- and means for rotating the receiving member at a rate proportional to the rate of movement of the film within said member.
20. In motion picture apparatus, a film reel constructed to deliver the film from the outer periphery of the film roll, a hollow rotatable receiving member for the film, means for positively drawing the film from the reel and delivering it to the inner periphery 5 of the receiving member and means for driving the receiving member from the reel, whereby the receiving member is driven at a rate proportional to the rate of movement of the film within said member.
- 10 21. In film winding mechanism, a magazine reel, and a winding barrel adapted to receive the film from the magazine reel and means to wind the same within the barrel so that the front end of the film will be disposed outwardly of the innermost wound portion of the film.
- 15 22. In film winding mechanism, a revolvable reel and a revolvable winding barrel adapted to receive the film from the reel 25 and means to wind the film within the barrel so that the front end of the film will be disposed outwardly of the innermost wound portion of the film.
- 20 23. In combination, a supporting member 30 for a roll of tape of flexible material, a receiving member for the roll, and means for unwinding the tape, feeding it to the receiving member, and rewinding the tape against the inner periphery of the said receiving member with the leading end out. 35
24. In combination, a supporting member for a roll of film, a rotatable receiver, means for conveying the leading end of the film to the receiver, and means for coiling the film in the receiver with the leading end 40 outermost.
25. In combination a supporting member for a roll of tape, a rotatable receiver, and means for coiling the tape in the receiver progressively inward toward the center of 45 the receiver.
26. In film winding mechanism, a magazine reel, a winding barrel, means for guiding the film into the barrel and means for winding the film within the barrel so that 50 the front end of the film will be disposed outwardly of the innermost wound portion.
- In testimony whereof I have signed my name to this specification in the presence of two subscribing witnesses.

CHARLES R. UEBELMESSER.
